UNITED STATES PATENT OFFICE.

THOMSON McGOWAN, OF CLEVELAND, OHIO.

MACHINE FOR MAKING COVERED WICKING, &c.

SPECIFICATION forming part of Letters Patent No. 541,568, dated June 25, 1895.

Application filed February 27, 1894. Serial No. 501,637. (No model.)

To all whom it may concern:

Be it known that I, THOMSON McGOWAN, of Cleveland, in the county of Cuyahoga and State of Ohio, have invented certain new and useful Improvements in Machines for Making Covered Wicking, Filled or Padded Braid, &c.; and I do hereby declare the following to be a full, clear, and exact description of the invention, such as will enable others skilled in the art to which it pertains to make and use the same.

My invention relates to improvements in machines for making covered wicking, filled or padded braiding, &c., wherein the wicking or filling is incased and secured within the covering or wrapper by folding the latter longitudinally around and sewing the same to the filling, and my invention consists in certain features of construction, and combinations of parts, hereinafter described and pointed out in the claims.

A preferable construction of machine embodying my invention is illustrated in the accompanying drawings, wherein—

25 Fig. 1 is a perspective of the machine. Fig. 2 is a top plan of a portion of the machine, partly in section, on line 2 2, Fig. 1. Fig. 3 is a side elevation of the means employed for grinding the filling and the covering fabric from the bobbins and for folding the covering fabric part way around the filling. Figs. 4, 5, and 6 are elevations of guiding-folders located in the path of the work to the needle of the machine. Fig. 7 is a view in perspective showing two of said folding devices and means connecting said folding devices with each other; and Fig. 8 is a transverse section on line 8 8, Fig. 7. Fig. 9 is a view in perspective of a portion of the means 30 employed for operating the feeding-rollers from the needle-bar of the machine. Fig. 10 is an enlarged perspective of suitable means for guiding the work from the last folder to and in under the presser-foot of the machine. 45 Figs. 11 and 12 are enlarged elevations in detail; and Fig. 13 is a section on line 13 13, Fig. 12.

Referring to the drawings, A designates the table of a sewing-machine; B, the over-hanging-arm or goose-neck of the head of said machine; C, the bed-plate of the sewing-machine head; D, the presser-bar; E, the

presser-foot; G, the needle-bar, and H the needle.

At the front side of table A are suitably supported two bobbins I and J, the one bobbin I carrying the covering or wrapping-material K, and the other bobbin J carrying the filling L. Said bobbins are preferably supported from upright arms or standards a suitably secured to table A, the bobbins being preferably arranged parallel with the head of the sewing-machine, and the bobbin carrying the covering-fabric being located a suitable distance above and somewhat rearward of the filling-carrying-bobbin. Between the presser-foot and the aforesaid bobbins is located suitable means for properly guiding the work to the needle of the machine and for folding the covering-fabric around the filling or material to be incased or covered preparatory to being sewed or stitched to the filling. Said guiding and folding means are very clearly shown in Figs. 2, 3, 4, 5, 6, 7, and 8, and comprise preferably slotted guides and folders, M, preferably 75 three or more in number.

Each of members M has a central oblong slot M' for the passage of the filling or material to be incased or covered, and has another narrower slot M², arranged about the centrally-located slot, for the passage of the covering-fabric or wrapper, said outer slot being so arranged and having such trend that it will fold the covering fabric about the filling, the one end of said outer slot overlapping, as 85 at M³, the other end of the slot such a distance that the portion of the strip of covering-fabric along the one longitudinal edge of the strip shall overlap the portion of the fabric along the other longitudinal edge of the strip 90 the distance required to enable the covering-fabric to be sewed or stitched near each of its longitudinal edges, to the incased material or filling. Any suitable number of said guides and folders M are arranged in line between 95 the presser-bar and bobbins, so that the covering-fabric and wicking or filling to be inclosed shall pass from the one folder M to the next rearward folder and from the last folder M to and in under the presser-foot. Each folder M is somewhat larger than the next rearward folder M, that is, the central slot M' in each folder M is less oblong and somewhat larger than the centrally-located slot M' in the

next rearward folder, and the outer slot M^2 in each folder M is separated farther from the centrally-located slot in said folder than the distance between the slots in the next rearward folder.

In the machine illustrated three folders M are employed. One of the folders, namely, that which is located next adjacent to the bobbins, is about midway between the presser-foot and bobbin-supporting-arms or standards, and the remaining two folders M are shown located a suitable interval apart between said first folder and the presser-foot. The centrally-located slot M' in each folder being somewhat narrower vertically than the centrally-located slot in the folder next preceding it, and the outer slot M^2 , in each folder being located in closer proximity to the inner or centrally-located slot in said folder than in the next preceding folder, as already indicated, it will be observed that the covering-fabric, in the operation of the machine, is caused to gradually less loosely embrace the wicking or filling as the work passes from the first to the last folder, the arrangement of the guiding and folding-slots in the last folder being such as to complete the required folding of the covering-fabric relative to the filling inclosed thereby. From the last folder the incased filling or material, with its covering or wrapper, passes to and in under the presser-foot of the sewing-machine through the path of the sewing-machine needle and thence passes to the feeding-device which consists, preferably of a pair of feeding-rollers herein-after described.

A guiding finger, N , (see Figs. 1, 3 and 10) for engaging the top of the work in its passage from the last folder to the presser-foot, to thereby guide or direct the work in under said foot, is preferably provided between said folder and presser-foot preferably in close proximity to the latter. Said guiding-finger is shown suitably secured to a guiding-bar or piece O that is arranged parallel with the path of the work and is adapted to engage one of the edges of and thereby form a lateral guide for the work. Member O is preferably rigid or integral with a plate O' suitably secured to the bed-plate of the sewing-machine head. The guiding-finger N is preferably adjustably secured in place, the same engaging or extending through a lateral hole O^2 in the upper portion of guide O and being secured in the desired adjustment by means of a set-screw N' that engages a correspondingly-threaded hole in member O for the purpose indicated, and plate O' is preferably adjustable in a direction transversely of the path of the work and is secured in the desired adjustment by means of a thumb-screw O^3 in any approved manner. The longitudinal adjustability of guiding-finger N renders the latter capable of adjustment as required for different widths of work, and the adjustability of plate O' enables the adjustment of said finger relative to the path of the work.

Guiding finger N , at its free end, is preferably bent downwardly, as at N^2 , to engage the edge of the work opposite to the edge engaged by lateral guide O already described, said downwardly-projecting member of the guiding-finger forming a lateral guide for the work in the opposite direction. By means of the guiding-devices just described, the work is accurately guided from the last folder M to the path of the sewing-machine needle.

The last folder M (see Figs. 1, 7 and 8) and the next preceding folder M , are preferably removably secured in place, the same being preferably rigidly connected with each other by means of a tapering tube P that connects the two centrally-located slots in said folders and tapers from the centrally-located slot in the forward folder toward the centrally-located slot in the rearward folder. Said folders are also connected by a plate Q the location whereof is such that the overlapping portions of the covering-fabric engage opposite sides of said plate, respectively, as shown in Fig. 8, and said folders are also connected by a plate R at the bottom. The outer or covering-fabric-receiving slots of said two folders are open at one end, as at M^4 , namely: at the end located uppermost for accommodating the insertion of said fabric preparatory to the operation of the machine. I would here remark that the work is placed in position within and relative to the different folding and guiding-devices before commencing to operate the machine, and that this is all the attendant has to do, the machine taking care of the work after that. As already indicated, it is desirable to have the last and next rearward folder removably secured in place so that they can be removed and other folders secured in place in case the machine was required to make work of greater or less width. To this end, one of said folders is provided with an upwardly and laterally-extending arm m that is preferably adjustably secured by means of a set-screw or thumb-screw m' to an upright flange S' of a plate S' adjustably secured, by means of a screw S^2 , in any approved manner, to the bed plate of the sewing-machine-head, said plate S being slotted in a direction at right angles to the path of the work to accommodate the adjustment of said folders relative to the path of the work.

One or more fingers T , preferably a pair of such fingers, are provided between the bobbins and adjustable folder M for guiding and partially folding the covering-fabric in its passage from the respective bobbin to said folder M . Fingers T are longitudinally slotted as at T' , to receive the fabric, said slots being open at the free ends of the fingers, and the fingers, at their opposite ends, are pivotally secured, as at T^2 , to arms U that are secured preferably to the bobbin-supporting standards. Fingers T are tightly pivoted to their supporting-arms so that they will retain the position or attitude in which they are placed, and their supporting-arms are pref-

erably adjustably secured to the bobbin-supporting-standard by means of set-screws U', in any approved manner, and slotted to accommodate a longitudinal adjustment of the same.

The filling, or material to be inclosed, is fed down upon the covering fabric from above the upper bobbin, said filling passing preferably upwardly from the bobbin that carries it to and over a guide W provided at the top of the bobbin-supporting-standards and located a suitable distance above and somewhat forward of the bobbin that carries the covering-fabric. From guide W the filling passes downwardly upon the covering-fabric, to be incased by the latter as already indicated.

Any suitable device is employed for feeding the work from the presser-bar and needle of the sewing-machine, and for feeding the same the distance required upon each elevation, or disengagement from the work, by the sewing-machine-needle.

A preferable construction of feeding-device is as follows: A suitable distance at the rear of the presser-foot, and in line with the path of the work, are located two feed-rollers, X, the one above the other, and suitably supported from and between housings or standards X' rigid with the table A, said feed-rollers being arranged transversely of the path of the work and adapted to engage opposite sides of the work, respectively, the rollers being so arranged relative to the top surface of the bed-plate of the sewing-machine-head that the work will be fed from the needle to the feed-rollers in a horizontal or approximately horizontal plane. The feed-rollers are milled, toothed or otherwise roughened upon their peripheral surface to take hold of or bite the work as required to feed the work. The feed-rollers are rotated intermittently in the direction to feed the work in any suitable manner, but are preferably operated from the needle-bar of the sewing-machine, and to this end I provide the following mechanism: The feed-rollers, at one end, are intergeared with each other, as at X², so that when motion is communicated to one roller the other roller shall also be rotated but in an opposite direction. A ratchet-wheel X³ is fixed or operatively mounted upon one of the trunnions of one of the feed-rollers, and, loosely mounted or fulcrumed upon the same trunnion at the outer side of said ratchet-wheel, is a lever X⁴ to the side of which, adjacent to the ratchet-wheel, is suitably secured a pawl X⁵ that is adapted to engage the teeth of the ratchet-wheel and operate said wheel as required. A spring X⁶, that engages and acts to retain the pawl in engagement with the ratchet-wheel, is preferably secured to said lever. Lever X⁴ is operatively connected, by means of a bar or link Y, with a collar, sleeve or member Y' slidably mounted upon an upright post b rigid with the overhanging arm or goose-neck of the sewing-machine-head, said link, at its lower end, being pivoted to the aforesaid lever, and, at its

upper end, being pivoted or swiveled to said sliding-member. The arrangement of parts is such that as said sliding-member and the upper end of the link pivoted thereto, are elevated, as hereinafter described, lever X⁴ is actuated in the direction to cause the pawl, that it carries, to move the ratchet-wheel and thereby actuate the feeding-rollers, and when the aforesaid sliding-collar, and link with which it is connected, descend by the gravity of the parts, the pawl shall be lowered one or more notches of the ratchet-wheel (according to the adjustment had) into position for the next succeeding movement of the feeding-rollers. The upper end of the needle-bar of the sewing-machine carries a laterally-extending arm or member g that is adapted to engage the under side of the link-carrying sliding collar Y', the arrangement of parts being such that upon the elevation or disengagement of the sewing-machine needle from the work, arm g of the needle-bar shall have come into engagement with said sliding-collar and shall lift said collar to effect the operation of the feeding-mechanism. Arm g of the needle-bar, at its inner end, is preferably adjustably secured to the needle-bar by means of a set-screw g' in any approved manner. A suitable device for guiding said laterally-extending arm or member of the needle-bar, during its ascent and descent, is preferably provided, said guide consisting of an upright rod or member Z that is located a suitable distance from upright post b to accommodate the operation or up-and-down movement of the aforesaid laterally-extending arm or member of the needle-bar between it (said guide) and its supporting-post, an arm b' being preferably adjustably mounted upon said post a suitable distance above the link-carrying sliding-collar, and guide Z is adjustable vertically, the same being secured to arm b' in the desired adjustment by means of a set-screw Z'. Guide Z, at its lower end, is bent laterally, as at Z², to form a rest for arm g of the needle-bar when said bar is in its lowermost position.

What I claim is—

1. The combination with a sewing-machine, and suitable means for feeding the covering-material and filling to and from the sewing-machine-needle, of a pair of folders M located a suitable interval apart in the path of the work to the sewing-machine-needle, each folder having an inner slot M', and having an outer slot, M², extending around the inner slot, the length and trend of said outer slot being such that the one end thereof overlaps the other end a suitable distance and above the inner slot, and the upper end of said outer slot being open, as at M³, a tube connecting the inner slots in said folders, all arranged substantially as shown for the purpose specified.

2. The combination with a sewing-machine, suitable means for feeding the covering-material and filling or material to be incased to and from the needle of the sewing-machine,

of a pair of folders, M, located a suitable interval apart in the path of the work to the sewing-machine-needle, each folder having an inner slot, M', and having an outer slot, M², extending around the inner slot, and the tube P and plate Q, arranged substantially as shown, for the purpose specified.

3. The combination with a sewing-machine, suitable means for feeding the covering material and filling or material to be incased to and from the sewing-machine-needle, of three folders M located a suitable distance apart in the path of the work to the sewing-machine-needle, each of said folders having a centrally located slot M' and having another slot M² arranged about the central slot with the one end of said outer slot overlapping the other end of said slot a suitable distance, the size

and relative arrangement of the slots in each folder being such that the covering fabric in the passage of the work to the sewing-machine-needle is caused to gradually less loosely embrace the filling or wicking in the passage of the work from the first to the last of said folders, the last two of said folders being connected by the tube P and plate Q arranged substantially as shown, for the purpose specified.

In testimony whereof I sign this specification, in the presence of two witnesses, this 28th day of December, 1893.

THOMSON McGOWAN.
